UNITED STATES PATENT OFFICE.

IRA EDW. WAGGONER, OF LEXINGTON, KENTUCKY.

WINDOW-CURTAIN HOLDER.

1,307,222.

Specification of Letters Patent. Patented June 17, 1919.

Application filed May 23, 1916. Serial No. 99,399.

To all whom it may concern:

Be it known that I, IRA E. WAGGONER, a citizen of the United States, residing at Lexington, in the county of Fayette and State 5 of Kentucky, have invented certain new and useful Improvements in Window-Curtain Holders; and I do hereby declare the following to be a full, clear, and exact description of the invention, such as will enable 10 others skilled in the art to which it appertains to make and use the same.

The invention relates to improvements in window curtain holders.

The object of the present invention is to 15 improve the construction of window curtain holders and to provide a simple, practical and comparatively inexpensive window curtain holder adapted to be readily applied to windows and is equipped with means for 20 supporting the lace curtains or other draperies of a window and capable of being operated to swing the curtains or draperies to and from the window so as to entirely remove the draperies from the window when 25 it is desired to clean the same or to obtain access to the window for any other purpose. It is also the object of the invention to provide simple and efficient means for 30 securely holding the lace curtains or other draperies at a window to prevent them from being accidentally blown out of proper position.

With these and other objects in view, the invention consists in the construction 35 and novel combination of parts hereinafter fully described, illustrated in the accompanying drawing, and pointed out in the claim hereto appended; it being understood that various changes in the form, proportion, size and minor details of construction, 40 within the scope of the claim, may be resorted to without departing from the spirit or sacrificing any of the advantages of the invention. In the drawing:

45 Figure 1 is a front elevation of pair of lace curtain holders constructed in accordance with this invention and shown applied to a window,

50 Fig. 2 is a detail perspective view of the upper portion of one of the holder parts being in section,

Fig. 3 is a detail vertical sectional view on the line 3—3 of Fig. 1, and

Fig. 4 is a detail sectional view illustrat-

ing the construction of the adjustable or extensible section.

Fig. 5 is a detail perspective view of the lower bracket.

Like numerals of reference designate corresponding parts of the several figures of the drawing.

In the accompanying drawing in which is illustrated the preferred embodiment of the invention the curtain holder comprises in its construction a vertically disposed combined operating and pintle rod journaled in bearing openings 2 and 3 of upper and lower bearing brackets 4 and 5 and provided at the top with a forwardly or outwardly extending approximately L-shaped arm 6 which carries a transversely disposed curtain supporting arm 7. The curtain supporting arm 7 which is disposed transversely of a window 8 as clearly illustrated in Fig. 1 of the drawing is designed to extend to the center of the top thereof as shown and attached with an extensible stub shaft 9 constructed of tubular metal slidably mounted on the arm 7 and provided with a head 10 preferably consisting of an ornamental ball or disk and adapted to prevent a curtain from slipping off the holder. The outer portion 11 of the L-shaped arm 6 extends downwardly and is adapted to enable the lace curtain to be properly positioned at the window but the said arm may be of any desired length and the outer portion may extend in any direction for this purpose.

The upper bearing bracket is approximately L-shaped and the lower bearing bracket which is similarly constructed is provided with an outwardly extending portion 14 having the said bearing opening 3 and laterally enlarged and split from the attaching portion or body of the lower bracket to form a resilient clamping jaw 12 which is bent downwardly and extended forwardly beneath the outwardly projecting portion of the lower bracket to clamp an operating handle or arm 13 formed by bending the lower terminal portion of the rod 1 at right angles. The horizontally projecting portion 14 of the lower bearing bracket constitutes a jaw and the lower resilient jaw 12 is curved as shown to clamp the operating arm yieldably between it and the said jaw 14. The outer end of the resilient jaw 12 is slightly curved and extended away

from the horizontal portion 14 of the lower bracket to form a flaring mouth or entrance to enable the handle of the rod to be readily swung into an engagement with the clamp.

5 What is claimed is:—

- A curtain holder comprising pairs of upper and lower brackets, vertically disposed operating rods journaled through the brackets, horizontal curtain rods connected 10 to the operating rods and adapted to be positioned in front of a window, locking devices formed integral with said lower

brackets and including a strip having a central portion bent upon itself and its outer portion bent to provide a spring clamp, and locking arms carried by the lower terminals of said vertical rods and adapted to be engaged by said locking devices.

In testimony whereof I affix my signature in presence of two witnesses.

IRA EDW. WAGGONER.
